ATTORNEY.

UNITED STATES PATENT OFFICE.

JAMES B. ROBINSON, OF CHATTANOOGA, TENNESSEE.

DESIGN FOR A BUCKLE.

56,993.

Specification for Design. Patented Jan. 25, 1921.

Application filed August 4, 1920. Serial No. 401,270. Term of patent 7 years.

To all whom it may concern:

Be it known that I, JAMES B. ROBINSON, a citizen of the United States of America, and a resident of the city of Chattanooga, in the county of Hamilton and State of Tennessee, have invented a new, original, and ornamental Design for a Buckle, of which the following is a specification, reference being had to the accompanying drawing, forming part thereof.

In the drawing the figure is an isometric view of my invention.

I claim:

The ornamental design for a buckle, as shown.

Witness my hand at the city of Chattanooga, in the county of Hamilton and State of Tennessee, this 30th day of July, 1920.

JAMES B. ROBINSON.
